UNITED STATES PATENT OFFICE.

PIERRE ARBEIT, OF PARIS, FRANCE, ASSIGNOR TO HARTFORD-EMPIRE COMPANY, OF HARTFORD, CONNECTICUT, A CORPORATION OF DELAWARE.

MANUFACTURE OF GLASSWARE.

Application filed April 24, 1925, Serial No. 25,573, and in France May 1, 1924.

- The present invention relates to the manufacture of glassware such as bottles, flasks, jars or the like, by the system in which a mold is charged with molten glass by suction, the mold being brought into contact with the surface of a body of molten glass in a furnace or other receptacle, and suction being produced within the mold to raise the glass therein.
- 5 In the existing installations the gathering of glass by the machines always takes place at the same point in the furnace. These repeated gatherings cause the glass to chill, and at the end of a certain time the machine ceases to work well.
- 10 According to the present invention, the machine suitable for the fabrication of the glass articles is displaced with respect to the furnace after each gathering operation, and the point of aspiration in the glass is thus constantly changed.
- 15 Moreover, burners are provided on both sides of the gathering zone in the furnace, the burners being put into action after each gathering operation, thus reheating the place in the furnace where the gathering has just been effected.
- 20 The displacements of the machine with respect to the furnace can be accomplished in any suitable manner, for example, by a pneumatic control as described in French Patent No. 581,003 and in my copending application filed on this date, Serial No. 25,574. These displacements of the machine may be accomplished equally well by means of an electrical control, a mechanical control, or even a hand control. The same is true with regard to putting into and out of operation the burners which serve to re-heat the gathering zone in the furnace.
- 25 The accompanying drawing shows diagrammatically, upon a section cut horizontally through the furnace, an arrangement for applying the method forming the object of the invention to an installation comprising a double series of molds.
- 30 As shown, the gathering operations in the furnace a , which is closed by a door a^1 , take place simultaneously at two places for the two series of molds. The vertical movements of the door a^1 put into and out of action the burners b , b , which are disposed on both sides of this door; the burners being lighted when the door closes in such a way 35 as to reheat the place where the gathering
- is done, and then being extinguished when the door is reopened for the molds to perform another gathering operation.
- As shown, two blank molds, serving two identical series of mechanisms, gather the glass at the points c^1 , c^1 . After this operation, the machine is displaced longitudinally, in such a way as to approach the furnace; the two gathering operations then take place simultaneously at the two points c^2 , c^2 . During the next gathering operation, the glass is gathered at the points c^3 , c^3 after another longitudinal displacement of the machine.
- 40 Through a transverse displacement of the machine, the glass is then gathered simultaneously at the points c^4 , c^4 . Then, the machine being left in the same position in the transverse sense, but being displaced longitudinally so as to recede from the furnace, 45 simultaneous gathering operations take place at the points c^5 , c^5 and then at the points c^6 , c^6 .
- 50 Through another transverse displacement of the machine, gathering operations are performed at the points c^7 , c^7 ; then, by advancing the machine longitudinally toward the furnace in the same transverse position, gathering operations are performed successively at the points c^8 , c^8 and then at the points c^9 , c^9 .
- 55 By thus changing constantly the point of suction in the glass, the chilling caused by repeated application of metal to the same place is avoided.
- 60 The order of the transverse and longitudinal displacements of the machine in respect to the furnace may evidently be modified, as well as the number of the displacements, which depends on the dimensions of the furnace. These displacements of the machine can be accomplished in any suitable manner, as by pneumatic control, by liquid pressure, by an electrical or mechanical control, or even by a hand control. The same 65 is true in regard to the control of the burners b , b for reheating the gathering places, control of which is preferably accomplished automatically through the movements of the furnace door a^1 before and after each gathering operation.
- 70 The invention has been described, by way of example, in connection with its application to an installation comprising two series of molds, but it is evident that it can be 75

used equally well in an installation including only one series of molds, or in an installation having a greater number.

Priority under the International Convention for the Protection of Industrial Property of March 20, 1883, is claimed for the present application, by reason of the filing in France on May 1, 1924, of a corresponding application for French Letters Patent, 5 upon which French Patent No. 581,002 was granted on September 17, 1924, to my assignee, the Société d'Etudes et d'Exploitations Verrières.

I claim:

- 15 1. The glass-working method which comprises periodically applying a gathering implement to the surface of a stationary supply of molten glass, and, in the intervals between such gathering operations, directing 20 a flame upon the region of the glass surface where said gathering takes place, to reheat such portion of the glass as may be chilled by contact with said gathering implement.
- 25 2. The method of gathering molten glass from a supply in a container having a normally closed work-opening above the glass level, which comprises uncovering the work opening, inserting a gathering implement 30 into said container through said opening, obtaining a gather of glass from the supply, withdrawing said implement, closing said work opening, and then directing a heating medium to the portion of the glass in the 35 container from which the gathering operation has taken place.
- 40 3. The method of gathering successive mold charges of glass from a supply in a container having a normally closed work-opening above the glass region, which comprises a periodic cycle of steps, including uncovering said work opening, inserting a gathering implement through said opening, gathering a portion of the glass from the 45 surface of said supply at a point removed from the point on said surface engaged by the preceding gathering operation, withdrawing said implement, closing said opening, and directing a heating medium to the 50 region of the surface of the glass in the container within which said gathering operations take place.

- 55 4. Glassworking apparatus comprising a stationary container for a supply of molten glass, said container being provided with an

opening through which gathering implements may be inserted, a door movable to and from position to close said opening, burner openings in the wall of said container adjacent to opposite sides of said first-named opening, and burners for projecting flame through said burner openings in converging directions upon the surface of the glass in said container.

5. Glassworking apparatus comprising a stationary container for a supply of molten glass, said container being provided with an opening through which gathering implements may be inserted, a door movable to and from position to close said opening, 70 burner openings in the wall of said container adjacent to opposite sides of said first-named opening, burners for projecting flame through said burner openings in converging directions upon the surface of the 75 glass in said container, and means for turning on said burners when said door closes and for turning off said burners when said door opens.

6. In combination with a glass melting 80 container having a work opening, means for supplying and for directing a heating medium to the glass near the work opening, a door for the work opening, and means operated in synchronism with the opening 85 or closing of the door for regulating the supply of heating medium.

7. In combination with a glass melting container having a work opening therein, a door for the work opening, means for 90 directing a heating medium to the glass in the container near the opening, and means actuated by the movements of the door for controlling the operation of the heat directing means.

8. In combination with a container for molten glass having a work opening above the glass level for the reception of a gathering implement, a door for the opening, said door arranged to be opened and closed at 100 each gathering operation, means for applying a heating medium to the surface of the glass near the opening, and means operated in synchronism with the opening or closing of the door for regulating the application 105 of the heating medium.

Signed at Paris, France, this 9th day of April, 1925.

PIERRE ARBEIT.
